SAFETY RAZOR

Joseph Muros, Cambridge, and Nicholas Testi, Boston, Mass., assignors to Gillette Safety Razor Company, Boston, Mass., a corporation of Delaware

Application May 10, 1943, Serial No. 486,290

10 Claims. (Cl. 30—70)

This invention relates to safety razors of the type in which a thin flexible blade is shaped and supported for shaving between blade-clamping members. The invention consists in improvements facilitating the presentation to the razor of fresh sharp blades while protected by an envelope which it is desired to remove only after the blade has been positively located in its shaving position.

The shaving edge of a thin safety razor blade is brought to such a high degree of fineness that it is extremely delicate and its keenness is likely to be destroyed if the edge is accidentally drawn across any part of the razor or the blade magazine or even the blade wrapper preparatory to shaving. Great care and considerable skill is required ordinarily on the part of the user to extract such a blade from its wrapper and present it safely in its shaving position without damage to its edge. The present invention deals with blades of a type which may be protected at the time or place of manufacture by being enclosed in a paper wrapper. This wrapper overlaps and safeguards the sharp edge or edges of the razor blade and must be removed to make the edge accessible for shaving. We contemplate a safety razor so organized that the wrapped blade may be delivered directly thereto in its final shaving position and temporarily held as thus positioned while the user has only to strip the wrapper from the blade and withdraw it from the razor, all this being effected without danger and even without the possibility of touching the keen cutting edge of the blade.

To this end an improved feature of the invention consists in a safety razor having blade-clamping members equipped with blade-positioning means and a detent or retainer engageable temporarily with the blade as inserted and positioned to prevent withdrawal of the blade while the cover is stripped therefrom. As herein shown the detent is mounted in the razor head for yielding movement and arranged to engage or interlock automatically with the blade when the latter reaches its shaving position and is properly positioned within range of the detent by the blade-locating means. The detent in no way interferes with the blade-clamping step and may be moved to an inoperative position at the conclusion of the shaving operation when it is desired to remove the used blade for cleaning or replacement.

Another feature of our invention consists in the combination with co-operating members movable to and from blade-clamping position, of a

blade-holding detent movable into retaining engagement with a blade presented between the blade-clamping members while the latter are separated and otherwise permit the free passage of the blade. The blade-holding detent may be operated to engage the blade either by the user or by spring means and in either case the detent is effective to retain the blade in its shaving position while the wrapper is stripped therefrom.

These and other features of the invention will be best understood and appreciated from the following description of a preferred embodiment thereof, selected for purposes of illustration and shown in the accompanying drawing, in which:

Fig. 1 is a view of the razor head in longitudinal section and on an enlarged scale;

Fig. 2 is a corresponding view in cross-section on the line 2—2 of Fig. 1, but showing a blade in place;

Fig. 3 is a plan view of the guard member of the razor with a wrapped blade in process of presentation thereto;

Fig. 4 is an end view of the razor head with portions of the handle shown as broken away; and

Fig. 5 is a view in side elevation partly in longitudinal section showing the detent retracted and the blade in the process of withdrawal.

The invention is not limited to safety razors of any specific type but is of general application and is herein shown in a razor of the "Gillette" type in which the blade-clamping members are permanently connected, although arranged to be separated for the reception or withdrawal of the blade.

The illustrated razor comprises a handle including a hollow barrel 10 permanently connected to a tubular head 11 which is rotatably secured to the blade-supporting or guard member 12. This is generally rectangular in outline and provided at its opposite edges with slotted portions defining outwardly and downwardly curved guard bars 13. The body of the guard is also formed with a flat surface bounded by parallel fulcrum shoulders 14 over which the blade is flexed in use and with a central longitudinal slot 15 which is interrupted by a hub portion surrounding the upper end of the head 11 and making permanent connection therewith. The guard 12 is apertured near one end to receive a cylindrical detent 16 mounted upon a leaf spring 17 which is riveted to the bottom of the guard and centrally cut-out so as to clear the head 11. In its normal position the spring 17 lies against the bottom of the guard as shown in Fig. 1 and supports the detent

16 in its inner position in which its upper bevelled surface extends slightly above the horizontal blade-supporting surface of the guard between its fulcrum shoulders 14. The upper surface of the detent 16 is bevelled downwardly toward the right so that it presents an inclined face to the advancing end of the blade as will presently appear.

The cap member 20 corresponds in contour with the guard 12 and has an inner concave surface arranged to co-operate with fulcrum shoulders of the guard in imparting a transverse curvature to the blade when the latter is clamped in shaving position. The cap is provided with a longitudinal blade-locating rib 21 which fits with clearance in the slot 15 of the guard and is interrupted so as to clear the central hub portion of the guard above the upper end of the head 11. The rib is also interrupted near one end to provide an open space for the detent 16. The cap is provided with a centrally disposed shank 22 which is flattened on both sides at its upper end as shown in Fig. 3 and received within the bore of the head 11. At its lower end it has a threaded connection with the head 11 and is provided with stop screw 23 at its lower end which cooperates with the lower end surface of the head 11 to limit the amount by which the cap and guard may be separated. On the other hand, when the handle is rotated with the head 11 the cap is drawn down forcibly into clamping relation with the guard.

The blade herein shown as adapted for use with the razor above described is shown in Fig. 3, partially in dotted lines. It is a double-edged blade 25 notched in each corner to provide elongated unsharpened end portions and having a central longitudinal slot opening through its left-hand end. The slot opens into spaced diamond-shaped perforations or apertures 27 and has a central circular enlargement 28 which affords clearance for the shank 22 of the cap when the blade has been moved fully into its shaving position. As herein shown the blade is enclosed in a paper wrapper 26 which is folded so as to protect both of its cutting edges and to extend in double thickness substantially beyond the right-hand end of the blade. The edges of the wrapper, however, do not extend inwardly far enough to cover the slot or apertures of the blade but leave them fully exposed. Blades thus protected may be dispensed in a book form of multiple wrapper package, such as that disclosed in U. S. Letters Patent No. 2,194,281, Gustafson.

Preparatory to shaving a wrapped blade 25 is pushed endwise between the cap and guard members of the safety razor while the latter are separated as shown in Fig. 1. The slotted blade moves forward smoothly upon both sides of the rib 21 of the cap while resting upon the flat supporting face of the guard 12. The blade slot not only affords clearance for the blade-locating rib 21 but also for the flattened shank 22 of the cap. The advancing end of the blade encounters the bevelled end face of the detent 16 and is itself bowed upwardly by the detent with a wedging action as the end of the blade rides upon the inclined face of the detent. During this step of blade-bowing by the detent the two sides of the blade are supported by the edges of the cap so that the center of the advancing end portion of the blade is curved over the detent 16. The height of the cap is, of course, limited by the screw 23 so that the blade is maintained always within range of the detent, that is, the blade cannot be inserted between the cap and guard

members without dragging over the detent. When the diamond-shaped aperture 27 of the blade registers with the detent the blade snaps down into flat condition and the detent passes freely through the aperture 27. When this occurs the detent makes interlocking engagement with the blade, thus positively holding it against reverse longitudinal movement. The rear edges of the aperture 27 furnish rigid shoulders in the blade making positive engagement with the rear wall of the detent 16 which, of course, is wider than the blade slot. With the blade thus held the user is free to remove the wrapper 26 by merely pulling it forcibly to the right. It is thus stripped from the blade while the latter remains positively and accurately positioned by the blade-locating rib 21 of the cap and detent 16. The handle is now rotated to draw the cap into blade-clamping position as shown in Fig. 4 and in this operation the detent may or may not be temporarily depressed although it re-assumes its elevated position as soon as released by the cap.

At the conclusion of the shaving operation the handle is rotated reversely and the cap 20 separated from the guard by the distance permitted by the limit screw 23. The blade, of course, is positively held during all this time by the detent 16. In order to remove the blade the user now depresses the spring 17 carrying with it the detent as suggested in Fig. 5. The free end of the spring is curved downwardly to afford free access thereto. As soon as the upper end of the detent 16 has been withdrawn below the plane of the blade and has disengaged the shoulder of the aperture 27, the blade is free to be withdrawn toward the right end of the razor or to slip out of the razor by its own weight if the razor is held on end.

In the foregoing description the detent 16 has been described as bowing the end of the blade when the latter is moved longitudinally into its shaving position. This is true so long as the spring 17 is stiffer in flexing than the blade, but equally good results are secured when the blade is stiff enough temporarily to depress the detent in bringing the aperture 27 into registration therewith.

Having thus disclosed our invention and described in detail one illustrative embodiment thereof we claim as new and desire to secure by Letters Patent:

1. A safety razor having co-operating blade-clamping members, blade-locating means, and spring actuated mechanism for engaging with a blade presented edgewise between two blade-clamping members and holding it against withdrawal.

2. A safety razor having co-operating blade-clamping members one of which presents a plane blade-guiding surface, blade-locating means, and a spring detent normally projecting above said blade guiding surface in position to interlock with a blade moved inwardly on said surface, and means for retracting said detent.

3. A safety razor having co-operating blade-clamping members defining a longitudinal blade passage between them when they are separated, blade-locating means, and a detent movable into and out of said blade passage to retain or release a blade perforated to receive said detent.

4. A safety razor having co-operating blade-clamping members connected to permit limited separation to define an intermediate blade passage between them, and a detent movable

through one of said members to engage a perforated blade presented endwise between them.

5. A safety razor in combination with a slotted open-ended blade, the razor having co-operating blade-clamping members with a blade-locating rib between them interrupted to provide an open space near one end of the razor, and a blade-retaining detent mounted for movement into and out of said space, the blade being slotted to receive the rib of the razor and perforated to receive the said detent when moved into its shaving position in the razor.

6. A safety razor for use with a wrapped blade, comprising co-operating members relatively movable to engage and clamp a blade, blade-locating means between said members, and a holding device movable to engage a blade presented between the blade-clamping members while they are separated and to retain the blade while its wrapper is withdrawn endwise.

7. A safety razor in combination with a blade having an internal perforation and a wrapper enclosing said blade and covering a sharp edge thereof and clearing said perforation, the razor having co-operating members movable to engage and clamp a blade between them, blade-locating means, and a holding device operatable from outside the razor to interlock with the blade perforation while the blade-clamping members are separated.

8. A safety razor having connected members relatively movable to clamp a flexible blade between them and when separated providing a longitudinal blade passage, a blade having shoulders

near one end, and a detent movable into engagement with said shoulders when the blade has been moved longitudinally into a predetermined position between said blade-clamping members while they are separated.

9. A safety razor having connected cap and guard members relatively movable to clamp a flexible blade between them, blade-locating means, a detent mounted in one of said members and normally held in a projecting position to bow a blade presented endwise beneath the cap, and a flexible blade provided with an aperture shaped to receive said detent when brought into registration therewith, whereby the blade may be interlocked with the detent while in flat condition.

10. A safety razor having cap and guard members relatively movable to clamp a flexible slotted and apertured blade between them, a blade-locating rib on one of said members, a detent of greater width than the rib located between said members, movable in a limited path and co-operating with the blade aperture to lock the blade against endwise movement, a handle having threaded connection with the cap member and swivelly connected to said guard member whereby the two members may be separated to receive between them a blade presented in flat condition, and a stop screw for limiting the separation of said members and thereby maintaining the detent within range of the aperture of a blade bowed transversely between said members.
